(57) **CLAIM**

The ornamental design for a mixing machine, as shown and described.

DESCRIPTION

The application file contains at least one drawing executed in color. Copies of this patent or patent application publication with color drawing(s) will be provided by the Office upon request and payment of the necessary fee.

FIG. 1 is a perspective front view of a mixing machine.

FIG. 2 is a perspective front view from the right side of the mixing machine of FIG. 1.

FIG. 3 is a right side of the mixing machine of FIG. 1.

FIG. 4 is a perspective rear view of the mixing machine of FIG. 1.

FIG. 5 is a left side view of the mixing machine of FIG. 1.

FIG. 6 is a perspective front view from the right side of the mixing machine of FIG. 1 in an opened state, with two lids of the drum located at the right side of the machine being opened toward the front and rear, respectively, and the left side of the machine being shifted to the left, so that the machine is shown opened in the middle; and,

FIG. 7 is a perspective rear view of the opened mixing machine of FIG. 6, with one lid of the drum located at the machine being opened toward the rear and the middle part of the machine being accessible by pulling the right and left parts away from each other.

The broken line showing of the mixing machine is included for the purpose of illustrating portions and environment of the mixing machine and forms no part of the claimed design.
